UNITED STATES PATENT OFFICE.

JOSEPH W. BATTERSHALL, OF ATTLEBORO, MASSACHUSETTS.

APPLIANCE FOR TREATMENT OF SPINAL AFFECTIONS.

970,781.

Specification of Letters Patent. Patented Sept. 20, 1910.

Application filed November 1, 1909. Serial No. 525,748.

To all whom it may concern:

Be it known that I, JOSEPH W. BATTERSHALL, a citizen of the United States, residing at Attleboro, in the county of Bristol and State of Massachusetts, have invented a new and useful Improvement in Appliances for Treatment of Spinal Affections, of which the following is a specification.

This invention relates to the class of appliances used in the treatment of spinal affections and pertains more particularly to braces or corsets used in the treatment of scoliosis or rotary lateral curvature of the spine. Many forms of corsets have been devised for this purpose, but generally they have had the same vital defect, which is that the pressure produced by them is chiefly lateral, and is equally as great upon the depressed portions of the body as upon the projecting parts, and thus all fail in correcting the rotation of the vertebrae. In correcting rotation of the vertebrae the pressure must be so directed as to rotate the vertebrae in a general direction around the longitudinal axis to restore the vertebrae to a normal structure. Mere lateral pressure against the ribs tends to increase rather than decrease the angular deformity of the ribs, by pushing inwardly upon the curving or twisting bones as well as upon those not affected.

The object of my invention is to bring the pressure upon the projecting parts only, in such a way that it untwists or rotates the vertebrae back to their normal position and thus strengthens the spine, while holding the unaffected part of the body in position to permit such untwisting.

Another object of my invention is to provide means for regulating the pressure upon any particular part of the body as desired, by providing a structure which is easily conformable to the unnatural shape of an affected body.

A further object is found in providing a device of this character which will relieve the spine of the weight of the upper parts of the body while it is exerting the continuous pressure which will return or untwist the vertebrae to their normal positions.

With these, and further objects as will hereinafter appear, in view, my improved construction will now be fully set forth and described, reference being had to the accompanying drawings, in which—

Figure 1 is a perspective view of my im-

proved corset, looking toward the front of the appliance. Fig. 2 is a rear perspective view, and Fig. 3 is a detail view showing the adjustable crutch member.

60

Referring more particularly to said drawings, in which like numerals of reference indicate like parts throughout, 1 indicates a belt-like member or girdle, said girdle consisting of a substantially oval-shaped steel

65

band 2, which may or may not be leather covered, and a padding 3 which is secured to the inside of said band 2 and overlaps its top and bottom edges in liberal folds in order to afford a comfortable encircling of the

70

body. Said padding 3 is formed of any suitable material, but is preferably a leather casing having a substantial packing. Said girdle is separated, as at a, and is provided with a strap and buckle, whereby to strap

75

the girdle around the body of a patient or wearer. Said girdle 1 encircles the body at points below the largest part of the hips and substantially across the pelvis, and has rising therefrom a plurality of uprights or

80

supporting rods 4 and 4'. Said rods 4 and 4' are secured to the steel band 2 by any suitable means, as rivets, bolts or screws, and are formed of stiff spring steel, so that they may be initially conformed to any desired shape, and will afterward maintain

85

that shape with a certain amount of resiliency. Said uprights or rods 4 and 4' are mounted on the girdle 1 in any suitable or necessary number and in any desired relation.

90

In the appliance illustrated, the rods are four in number, the two rods 4' being placed substantially in the central front portion of the girdle, and extend upwardly to a height of a line across the middle of the

95

chest. A series of horizontal metallic straps or braces 5 formed of material similar to that used in the construction of upright rods 4, are secured in spaced relation across the outside of said rods 4 and 4' and are ex-

100

tended variously across two or more of said rods, as needs require. For instance, the preferred embodiment shown, two straps extend around all four of the upright rods 4 and 4', while strap 5" is located between the

105

strap 5' and only embraces the rods 4 and one of the front uprights 4'.

Secured to the upper end of the right hand one of the front rods 4' and extending to one side thereof, is an arcuate spring plate 6, said plate forming a rigid structure with said rod 4' and extending in a direc-

110

tion opposite to that taken by the strap 5 thereby providing a support or bearing plate to resist the twist of the body around the region of the chest or upper part of the 5 trunk.

The rod 4 located in the rear of the girdle 1 extends upwardly to lie next to and substantially the entire length of the spinal column, and is bent into curves suitable to 10 the curvature of the body to be straightened. Secured, as by rivets, to the upper end of the rod 4, or that portion which extends above the upper strap 5' is a triangular web or pad 7, said web having its lower side 15 similarly fastened to said upper strap 5' and forming a securing means for a series of straps 8, which adjustably hold in position a back and shoulder pad 9 by means of the buckles 10 secured thereon, as by sewing or 20 riveting. Said pad 9 consists of a flexible padded element, preferably formed of soft leather, and conformed to embrace the upper portion of one side of the back and the right shoulder. A shoulder strap 11, is 25 formed on the upper edge of said pad 9 and extends over the shoulder and is fastened, as by a buckle and strap to the extended spring plate 6. The free vertical edge of the spring plate 6 is provided with a plurality 30 of straps 12 which are attachable to buckles 13 carried by said pad 9 to adjustably set said pad 9 and to form a means of entering the corset. Other pads as 14 and 15, are 35 suitably disposed to protect the body at the points where the corset acts to straighten the body. Pad 14 consists of a rectangular leather cushion fastened between uprights 4 and 4' and having a secondary pad 16, secured leaf-fashion to one edge thereof as an 40 additional cushioning element. Said pad 14 relieves the pressure of said rods 4 and 4' on the front of the body, as the latter co-operate with the spring plate 6 to twist the distorted body of the patient. A brace rod 45 17 extending between rod 4' and the plate 6 strengthens and stiffens the plate 6 to increase the twisting pressure of the latter. The pad 15 is a cushioned element, similar 50 in structure to pad 14, and extending across one side of the appliance to protect the body of the patient from the side rod 4 and to exert a straightening pressure on the patient's side. Said pad 15 is secured, as by rivets to the horizontal strap 5, as desired, the 55 present embodiment, showing it secured to strap 5'' and lower strap 5'.

Mounted on the upper end of the side rod 4, is a crutch member 18, which is adapted to support the patient's shoulder and upper 60 part of the body, and relieve the spine therefrom. Said crutch member 18 has a stem 19 provided with a plurality of apertures 19' by means of which the crutch may be 65 adjustably bolted to the rod 4.

From the above exposition, it is evident

that an appliance has been provided comprising essentially a metallic spring frame provided, as needed, with suitably disposed pads said frame being adjustable by shaping the malleable spring frame to the patient's body, and the pads being also capable of being positioned as desired or needed to bear on the projecting parts of the body and to relieve the depressed parts. It is also evident that the spring members act to 70 twistingly rotate the body and consequently the spine as well as to bear laterally upon the spine and body parts.

Having thus described my invention, I claim as new and desire to secure by Letters 80 Patent:

1. A curvature appliance, comprising, in combination, a girdle, a plurality of uprights disposed around said girdle, a spring pressure plate, an integral back pad and 85 shoulder straps adjustably carried by the upper ends of said uprights and a crutch member to support the body off of the spine.

2. A curvature appliance, comprising, in combination, a girdle, a plurality of resilient 90 uprights carried by said girdle, a laterally projected spring plate secured to a front upright, a crutch member adjustably secured to a side upright, a back pad carried by one of said uprights and having a shoulder strap 95 adapted to be attached to said spring plate, and a plurality of pressure pads carried inside said uprights.

3. A curvature appliance, comprising, in combination, a girdle, a plurality of uprights carried by said girdle, a series of cross straps carried by some of said uprights, a laterally projected spring plate adapted to co-operate with said straps to twist the patient's body, a back pad vertically hinged at 100 the back of the appliance, and having adjustable attaching devices along its opposite edge, a shoulder strap integral with said pad and adapted to be secured to said spring plate, and pressure pads disposed inside said 110 uprights.

4. A curvature appliance, comprising, in combination, a girdle, a plurality of uprights disposed around said girdle, a plurality of cross straps secured near the upper 115 ends of said uprights, a laterally projected spring plate secured to the upper end of one of the front uprights, an adjustable crutch member secured to the upper end of one upright, a back pad secured to the back of the 120 appliance by a plurality of adjusting straps, a shoulder strap carried by said pad and adapted to be secured to said spring plate.

In testimony whereof I have signed my name to this specification in the presence of 125 two subscribing witnesses.

J. W. BATTERSHALL.
